TIMER

Carl Ludwig Anderson, Moline, Ill., assignor to
Eagle Signal Corporation, Moline, Ill., a corpora-
tion of Massachusetts

Application July 19, 1940, Serial No. 346,333

7 Claims. (Cl. 200—38)

This invention relates to cycle timers in which an actuated member is actuated at predetermined times in a repeating cycle of operations. Time switches constructed in accordance with this invention are suited for controlling the periods of energization and shut down of electric circuits, for controlling relays, for turning valves in gas or liquid lines, and for other related service. This invention further relates to a snap switch of particular utility in conjunction with the timer of this invention.

It has been common in the art to construct cycle timers having a cam shaft driven in one direction by a motor at the proper speed to provide the required time cycle. Such constructions have been unsatisfactory for many applications because of the difficulty in varying, conveniently, the cam shaft speed over a wide range, and also because any change in the cam shaft speed or time cycle varies the "on" and "off" time proportionately.

Among the important objects of this invention are to provide a cycle timer in which the time cycle is adjustable over a wide timing range; to provide a timer in which the periods of the cycle are adjustable independently of each other; and to provide a timer in which the adjustments in timing are easily and conveniently made on a calibrated dial, particularly a dial which may be calibrated to show separately the timing of the various periods. It is a further object to provide a switch mechanism operated by the actuating member of the cycle timer as the actuating member passes the same point moving in either direction.

To those skilled in the art, other objects and features of this invention will be readily apparent from the following specification and annexed drawings illustrating certain preferred embodiments of the invention in which:

Fig. 1 is a front elevation showing the dial assembly;

Fig. 2 is a rear elevation of the timer with the case removed;

Fig. 3 is a left end elevation with the end of the case broken away to show the timer mechanism;

Fig. 4 is a section on the line 4—4 in Fig. 2;

Fig. 5 is a section on the line 5—5 in Fig. 4 with portions of the driving mechanism broken away to show the pawl assembly;

Fig. 6 is a section on the line 6—6 in Fig. 4;

Figs. 7 and 8 show details of the pawl assembly;

Fig. 9 is a detail of the assembly involving the timer plate and the time controlled member;

Fig. 10 is a rear elevation of the timer with a different type of switch substituted, and with the case removed;

Fig. 11 is a partial plan of the timer of Fig. 10 showing the switch;

Fig. 12 is a fragmentary section showing the switch taken on the plane of the line 12—12 in Fig. 10;

Figs. 13, 14, and 15 show the operating mechanism for the switch in various positions, together with a showing of the relative location of the switch arms; and

Fig. 16 is an edge view of the structure shown in Fig. 13, looking in the direction of the arrows 16 in that figure.

In Figs. 1 to 8, an embodiment of the invention is disclosed involving a repeating cycle timer in which the phases of a two-phase cycle are independently timed. In this embodiment, an open front case 14 is provided to which is hingedly connected a door 15 having therein a slight opening closed by a transparency 16 suitably secured in the opening. A timer frame is arranged to be secured to the open front of the case 14 by the frame plate 17 being attached to brackets 18 secured within the case. A second frame plate 19 is rigidly attached to plate 17 by a plurality of frame posts 20, the two plates 17 and 19 being parallel and spaced apart.

In order that the timer may be readily removed from the case, all electrical connections are made to the timer through contacts carried by block 21, secured in the back of the case. Four contacts are provided on the block, each of the type shown in Fig. 3, in which a terminal plate 22 and bolt 23 are secured to the block 21 by a bolt 24, and in which a spring contact arm 25 is clamped between the terminal plate and the block and is provided with an upwardly and forwardly inclined contact finger 26. Cooperating contact members are carried by the timer by a block 27 supported by posts 28 attached to the rearward frame plate 19. These contact members comprise contact fingers 29, downwardly and rearwardly inclined into engagement with fingers 26, the fingers 29 being secured to the block 27 by suitable bolts.

Referring now to Fig. 2, to one such pair of contact members 30 on block 27 is communicated power through the mating terminals. The motor 31 which drives the timer is directly connected with the contact members 30, whereby, when current is communicated to the timer, the motor

31 will be continuously driven in one direction. A second pair of contact members 32 on block 21 is connected by conductors to the two switch arms 33. These switch arms 33 are pivoted on a post 34 extending rearwardly from the plate 19 and have a spring 35 positioned between their lower ends below the pivot post. A cam 36 carried on shaft 37 is positioned between the upper ends of the switch arms, and the cam is so shaped that upon rotation the contacts 33 move together and apart.

In general terms, the timer shown operates by producing alternate movement of a member in opposite directions, the member producing actuation of the shaft 37 upon each passage of the member past an intermediate index point. The extent of movement in each direction from the index point at which actuation occurs may be adjusted whereby to adjust each of the periods of the cycle.

To produce movement in opposite directions, a pair of similar gears 38, 39 is mounted for rotation about a shaft 40 fixed in the rear frame plate 19. The driving of these gears 38, 39 is effected through a gear 41 fixed on the motor shaft which drives a gear 42 through gear 43 whereby gears 42 and 43 rotate in opposite directions. The gear 42 has a gear 44 non-rotatably secured thereto with the two being rotatably carried on a post secured to frame plate 19, and the gear 44 in driving engagement with the aforementioned gear 38. Likewise, a gear 45 is non-rotatably secured to gear 43, the two being rotatably carried on a post secured to frame plate 19 with the gear 45 in driving engagement with gear 39. By this arrangement, continuous opposite rotation of gears 38 and 39 is effected.

The gear 38 is non-rotatably secured to a ratchet wheel 46 through a sleeve 47 rotatably carried by shaft 40. A second ratchet wheel 48 is non-rotatably secured to the other gear 39 through a sleeve 48' which fits rotatably around the sleeve 47 between gear 38 and ratchet wheel 46. The inner sleeve 47 is made separable so that the outer sleeve may be placed thereover. The two ratchet wheels 46 and 48 have the teeth thereon directed in opposite directions to effect driving in opposite directions.

A timing plate 49, carrying an indicator finger 49a and secured to the sleeve 50 which is rotatably carried on the shaft 40 between the ratchet assembly and the front frame plate 17, carries for rotation therewith a reversibly acting pawl assembly 51, means for effecting reversing of the action of the pawl assembly, which means is best shown in Fig. 6, and means for cooperating with the switch operating shaft to effect actuation of the switch.

The pawl assembly 51, which is carried for oscillation as a unit on a pin 52 extending rearwardly from the timing plate 49, is built up of a pair of plates 53 secured together in spaced relation by a pair of pins 54. Intermediate the ends of the plates 53, a sleeve 55 is secured in openings in the plates. A pair of dogs 56 is interposed between the plates, both of which are supported at one end by the sleeve 55 and each of which is supported at its other end by one of the pins 54. The sleeve 55 is provided with a collar integral therewith positioned between the dogs 56 which is of a thickness to space the dogs a distance equal to the distance between the two ratchet wheels 46 and 48. A collar is placed on each of pins 54 to maintain the outer ends of the dogs in line with the ratchet wheels. Each of the dogs is pro-

vided with one or more teeth suitable for engaging with the cooperating ratchet wheel.

The forward plate 53 is provided with an arm 57 extending generally toward the shaft 40. This arm 57 carries a pair of posts 58, 59 extending forwardly therefrom through openings in the plate 49 (see Fig. 6). The openings through which these posts 58 and 59 extend are so located and are of sufficient size to permit oscillation of the pawl assembly 51, about the shaft 52, into driving engagement with either of the ratchet wheels.

The means heretofore mentioned for oscillating the pawl (see Fig. 6) involves a lever 60 secured to a sleeve rotatably carried by the sleeve 50 (Figs. 3 and 4) between the timing plate 49 and the forward frame plate 17. The arm 61 of lever 60 extends outwardly from shaft 40 sufficiently to engage adjustable stop pins 62, 63 which are hereinafter more fully described. A second arm 64 of lever 60 has a finger of gear-tooth type which engages between two similar fingers carried by a lever 65 pivotally mounted on post 66 secured to timing plate 49. Upon counterclockwise movement of lever 60 with respect to timing plate 49 from the position shown in Fig. 6, the lever 65 will be raised. Two links 67 are separately pivoted to the lever 65, adjacent the end thereof, and are biased together by a spring connecting their free ends. These links 67 are each provided with a roller near their free ends, these rollers effecting rapid movement of the pin 58 therebetween, upon movement of the lever 65. Thus upon raising of the lever 65, as viewed in Fig. 6, the links 67 will move upwardly until the dead center between the rollers passes the greatest diameter of pin 58, whereupon the pin will be forced downward.

In order to increase the speed of actuation of the pawl assembly with respect to movement of the lever 60 and thereby increase the accuracy of the time of operation, an arm 68 is formed with the lever 60, and is provided with a notch 69 in which the pin 59 carried by the pawl assembly is movable. The notch 69 is so located that when the lever 60 is oscillated relatively to the timing plate 49 in either direction it moves free of the pin 59 until just slightly prior to dead center positioning of the rollers on the pin 58, whereupon the end of the notch pushes the pin 59 enough to send the pin 58 past dead center.

From the above description it can be seen that when the pawl is engaged so as to rotate the timing plate 49 clockwise and the lever arm 61 engages a stop terminating rotation thereof, the engagement of the pawl assembly will be reversed, reversing the direction of rotation of timing plate 49. The same occurs upon rotation in the opposite direction.

In order to effect ready adjustment of the stop pins 62 and 63 about the shaft 40, the front frame plate 17 is formed with an annular opening 70 therein. The portion 71 of the plate within the annular opening is supported by the shaft 40 and a shouldered nut 72 on the forward end of the shaft. A pair of arms 73, 74 is supported on the nut between the shoulder and the portion 71 of the frame plate 17 for free rotation about the shaft 40. The free end of arm 73 is provided with a bolt having the pin 62 extending axially from the head thereof, and with the head rearwardly of the annular opening. The shank of the bolt extends through the annular opening, through an opening in arm 73, and has a knob 75 on the forward end thereof. The arm 73 is

further provided with an indicating pointer 76 for cooperation with the scale 77. The arm 74 is provided with a similar bolt and knob assembly for supporting the stop pin 63 and for securing it in adjusted position, and is provided with an indicating pointer 78 for cooperation with the scale 79. The scales 77 and 79 have their "0" markings in radial alignment and are calibrated in opposite directions.

While any suitable means may be provided for turning the shaft 37 when the timing plate 49 passes a fixed position, traveling in either direction, there is shown in the embodiment disclosed a "Geneva" like type of operating means which is of particular utility in this device as it produces rapid turning of the shaft and as it holds the shaft in the turned position at all times, preventing the switch from becoming out of phase.

In the switch operating means shown, a notch 80 is formed in the edge of the timing plate 49, and two pins 81 are secured to the rear surface of the plate adjacent to the notch. A gear-like member 82 is positioned on the shaft with three equally spaced teeth 83, 84 lying in the plane of the plate and two teeth 85 positioned in a plane rearwardly of the plate for coaction with the pins 81, and half way between the tooth 83 and each of teeth 84.

When the plate rotates counterclockwise from the position shown in Fig. 9, the tooth 83 is moved into the notch 80 when the tooth 85 adjacent the plate contacts pin 81. The shaft 37 will be turned one-third of a rotation, after which the tooth 83 and the right hand tooth 84 will ride on the periphery of the timing plate 49. The timing plate 49 is made circular to coact at all times with tooth 83 and one of the teeth 84 in maintaining the shaft in its moved position.

The notch 80 and cooperating switch operating member may be placed at any point about the shaft 40. It is desirable, however, to have the notch in the disc spaced circumferentially of the disc from the lever arm 61 which effects reversal a distance equal to the spacing of the switch operating shaft from the "0" scale markings, whereby the switch is operated at the time the lever arm passes this marking.

In order to indicate the position in the cycle of the timer at any particular time, the free end of the lever arm 61 is bifurcated and a pointer 49a is secured to the timing plate 49 at the mean operating position of the lever arm. The notch in the end of the lever arm 61 is of sufficient size to permit adequate operating movement of the lever arm whereby, if the pawl assembly is manually turned out of its operative position, the pin 58 will not pass dead center between the rollers supported by toggle arms 67. Further, the notch is sufficiently small as to bias the pawl assembly at all times in its then operative position. The pointer 49a is positioned to extend through the annular opening in the frame plate 17.

In operation, the motor 31 drives the gears 38 and 39 continuously in opposite directions and therefore, through the sleeve connections, also the ratchet wheels 46 and 48. The pawl assembly will be in operating position controlled by the lever arm 61. As shown in Fig. 6, the lever arm 61 will hold the pawl in contact with the ratchet wheel which rotates clockwise, thereby effecting movement of the timing plate 49 clockwise. When the lever arm 61 contacts the adjustable stop pin 63, it will be stopped, but the timing plate 49 will continue to rotate, thereby turning the

lever arm 61 counterclockwise with respect to the timing plate. This as heretofore described, shifts the pawl assembly into engagement with the other ratchet wheel, resulting in counterclockwise rotation of the timing plate. When the pointer 49a reaches the "0" marking, the switch shaft 37 will be turned, thereby turning cam 36 and operating the switch. Counterclockwise rotation will be continued until lever arm 61 is reversed by stop pin 62, whereupon clockwise rotation will be resumed.

In the embodiment of the timer of this invention, shown in Figs. 10 to 15, there is disclosed a snap action switch, substituted for the switch shown in Figs. 1 to 9. When the timing plate 49 is run slowly in order to increase the maximum total cycle, it is desirable to employ a snap action switch. However, the heretofore known types of such switches are not particularly desirable for this service as they do not snap upon movement in opposite directions in the same position of the movable member, which in this timer would result in the switch being opened and closed at different positions of the timing plate 49. While it should be understood that the scales can be calibrated to allow switch actuation at considerably divergent points about the timing plate, actuation at the same position is desirable for purposes of simplicity of calibration.

As shown, in Figs. 11 and 12, three contact arms 86, 87, 88 are provided which are pivoted on shaft 99 carried in bracket 90 which is secured to the rear surface of the frame plate 19. Springs 91, individual to each of the contact arms, bias the upper end of each arm forwardly toward frame plate 19. The contact arm 86 is provided with a contact point 92 facing rearwardly, i. e., away from plate 19, at its upper end. The middle contact arm 87 is provided with a pair of contact points, one point 93 facing forwardly and being supported in alignment with contact point 92 for cooperation therewith, and the other 94 facing rearwardly. The third contact arm 88 is provided with a single contact point 95 facing forwardly in line with contact point 94 for cooperation therewith. Positioning stops 96 and 97 secured to frame plate 19 are provided in conjunction with each of contact arms 86 and 88 to limit forward movement of the upper ends of these contact arms. Stop 96 cooperating with contact 86 is sufficiently short that, in the normal positions of arms 86 and 88, the contact points carried by arm 87 do not form a bridge therebetween. In normal spring-urged positioning of contact arm 87, the circuit is closed between contact points carried by arms 86 and 87, and in moved positioning of arm 87, which is hereinafter referred to as supported position, the circuit is closed between the contact points carried by arms 87 and 88, as shown in Fig. 11, by means hereinafter described. Suitable electrical connection from the contact points is made to terminals on the block 27.

A contact operating arm 98 pivoted on stud 99 carried by frame plate 19 extends below cam 100, which is secured to shaft 37, to a position between the frame plate 19 and the contact arm 87. A spring 101 is provided to urge the operating arm 98 upwardly into contact-supporting position. The free end of contact operating arm 98 is provided on its rearward surface with a cam surface 102 inclined to cooperate with contact arm 87 to move this contact arm into supported position upon spring-urged movement of the operating arm. Arms 98 and 103, pivoted, respec-

tively, on posts 99 and 104, lie in the same vertical plane. The arm 98 has on its forward surface a boss 111, while arm 103 has on its rearward surface a lug 105.

The post or stud 104 is carried by the frame plate 19 and extends above the cam 100 and therebeyond to a position adjacent the upper end of contact arm 87. The lug 105 on arm 103, when positioned between the contact arm 87 and the frame plate 19, holds the contact arm in supported position. Flanges may be provided on the free ends of arms 98 and 103 as shown at 103b, Fig. 11, to space these arms properly from the frame plate 19, the flanges moving in contact with the frame plate.

A latching member 106 is pivoted on the stud 107 and comprises a pair of arms 108 and 110. This latching member swings in a vertical plane between the plate 19 and the arms 98 and 103. The post 97 limits the downward swinging of arm 103 and the lateral swinging of arm 110 occasioned by spring 103a. This will insure that the lower extremity of arm 110 may be in the path of the boss 111 when the arm 98 is released for upward swinging motion, if member 106 has not been moved laterally by cam 109 until the lower end of the arm 110 is out of the way of lug 111. This post 97 also limits the forward swinging motion of the contact arm 88, biased by the spring 91. This permits the separation of contacts 94 and 95 when arm 87 moves forwardly to close the gap between contacts 92 and 93. The spring 103a, provided between the contact supporting arm 103 and the latching member 106, is to bias both in clockwise direction.

In the operation of the snap switch, starting from the position shown in Fig. 13, which is the position during one of the timed periods of the cycle, in which the operating arm 98 is lowered and the contact arm 87 is supported by the supporting arm 103, the lug 105 being between arm 87 and arm 103, the shaft 37 will turn from the position shown counterclockwise, upon the indicator finger 49a passing the "0" index. Upon counterclockwise movement of the plate 49 and the indicator 49a, the cam 100 allows the operating arm to rise until the boss 111 engages the latching arm 110. At substantially identical positions, the shoulder 112 comes into alignment with the shoulder 113 on the arm 98 and a high part of the cam 100 moves the contact supporting arm 103 upward out of supporting position, as shown in Fig. 14. The contact arm 87 at that time, therefore, moves to normal position under action of its cooperating spring 91. Further movement of shaft 37 brings the cam 109 into engagement with latch arm 108 effecting movement thereof which releases the boss 111 from the latching arm 110, as shown in Fig. 14. Release of the latch allows the shoulder 113 on the contact operating arm 98 to move into engagement with shoulder 112 on cam 100, thereby holding the arm 98 out of supporting position. Upon clockwise movement of the shaft 37, after staying in the position shown in Fig. 14 during the second period of the cycle, at the switch-operating position of cam 100, above described, the shoulder on arm 98 clears the shoulder 112 on the cam 100, allowing the arm 98 to move into supporting position as shown in Fig. 15. Further movement of the cam 100 clockwise depresses the arm 98 to a position releasing the latching arm 110 from the boss 111 for clockwise movement, as shown in Fig. 13.

While I have above described a specific em-

bodiment of my timer in conjunction with two specific switches particularly suited to being controlled by this timer, it is to be understood that the scope of this invention is not limited to this particular disclosure, but should be considered as limited only by the scope of the subjoined claims.

Having now described my invention, I claim:

1. A timer comprising, a timer means movable in opposite directions, driving means for moving said timer means in either of said directions, two reversing means, said timer means including means movable therewith for operative engagement with one of said reversing means upon movement in either of said directions and co-operating therewith upon such operative engagement for effecting reversal of the direction in which said driving means moves said timer means, and means actuated by said timer means upon movement in each direction thereof at a position 10 of the timer means intermediate the positions 15 of said timer means when in operative engagement with said reversing means.

2. In a timer, the combination comprising a rotatable timer means, a pair of rotatable drive 25 means mounted for rotation on the same axis as the timer means, means for driving said drive means in opposite directions, engageable means carried by said timer means for engagement with and disengagement from one of said drive means for effecting rotation of said timer means in one direction upon engagement thereof, engageable means carried by said timer means for engagement with and disengagement from the other of said drive means for effecting rotation of said 30 timer means in the opposite direction upon engagement thereof, and a pair of stop means, said timer means including actuating means movable into operative engagement with said stop means, said stop means and said actuating means cooperating upon operative engagement of the actuating means with either of said stop means to shift one of said engageable means out of engagement and the other into engagement.

3. A timer comprising a timer means, driving 45 means for driving said timer means in opposite directions, means actuated by said timer means by movement of said timer means in one of said directions through a fixed position of said timer means, said actuated means also being actuated by movement of said timer means in the other of said directions through a fixed position, and a pair of adjustable reversing means to effect reversal of the direction in which the driving 50 means drives said timer means at independently adjustable times with respect to the actuation of said actuated means.

4. A timer comprising, a timer means supported for rotation in either direction, a pair of driving discs mounted for rotation in opposite directions on the same axis as said timer means, a driving means carried by said timer means shiftable to either of two positions in which it is severally cooperable with one of said discs to drive said timer means in the one or the other of said directions depending on the position in which it is shifted, shifting means carried by said timer means for movement to either of two positions with respect to said timer means and for rotation therewith in either of said positions, movement of said shifting means from either of said 60 positions to the other of said positions thereof effecting shifting of said driving means from one of said positions thereof to the other of said positions thereof, and adjustable means fixable 65 non-rotatably for effecting movement of said

shifting means from either of the positions thereof to the other of said positions thereof.

5. A timer comprising a timer means movable in opposite directions, means actuated by said timer means upon movement of the timer means in opposite directions respectively through a position thereof, means for moving said timer means in said opposite directions, and means for limiting the extent of movement of said timer means in each direction from said position and for effecting reversal of movement at the extent so limited from either direction of movement to the other.

6. A timer comprising a timer means, driving means for driving the timer means through a fixed position in opposite directions at controllable times, a cam, means controlled by said timer

means to effect opposite oscillation of said cam upon movement of said timer means through said position in opposite directions, a switch, and snap action means for effecting opening and closing of said switch upon oscillation of said cam in opposite directions at the same rotative position of said cam in both of said directions, respectively.

7. A switch, snap action means for opening and closing said switch, and a cam mounted for oscillation in opposite directions cooperating with said snap action means to effect opening and closing of said switch at the same rotative position of said cam upon movement of said cam in both of said directions, respectively.

CARL LUDWIG ANDERSON.
